G. J. DORMANDY.
ELECTRIC LAMP FIXTURE.
APPLICATION FILED JUNE 7, 1913.

1,072,926.

Patented Sept. 9, 1913.

UNITED STATES PATENT OFFICE.

GARRY J. DORMANDY, OF TROY, NEW YORK, ASSIGNOR OF ONE-HALF TO UNITED SHIRT AND COLLAR COMPANY, OF TROY, NEW YORK, A CORPORATION OF NEW YORK.

ELECTRIC-LAMP FIXTURE.

1,072,926.

Specification of Letters Patent. Patented Sept. 9, 1913.

Application filed June 7, 1913. Serial No. 772,296.

To all whom it may concern:

Be it known that I, GARRY J. DORMANDY, a citizen of the United States, residing at Troy, Rensselaer county, New York, have 5 invented certain new and useful Improvements in Electric-Lamp Fixtures, of which the following is a specification.

My invention relates to fixtures adapted to stand upon and be secured to a table or 10 the like and to support a conduit which extends therebetween, each of said fixtures being also adapted to carry one or more incandescent lamps connected with a cable passing through said conduit and so that the 15 lamp may be adjusted to and secured in any desired position. Its objects are to afford a convenient support for the conduit, to absolutely inclose and protect the wires therein, and to provide complete adjustability to the lamps. 20

Further objects of the invention and the means by which all are secured will appear in this specification and be pointed out in the claims.

25 In the example of my invention chosen for illustration, Figure 1 is a front elevation of one of my lamp fixtures; Fig. 2 is a partial and enlarged elevation of the same; Fig. 3 is a transverse vertical section through the 30 plane 3—3, Fig. 2; Fig. 4 is a partial rear elevation of the device; Fig. 5 is a vertical transverse section through the plane 5—5, Fig. 4.

Premising that the fixtures are largely 35 used in factories and mills on long tables carrying double rows of machines, as sewing machines, 11 designates a part of such a table on which is secured, as by screws 12, a standard 13 consisting of a flanged column 40 14, which is a short cylindric box portion 15, from which extend in opposite directions sockets 16, into which are threaded set-screws 17. Above sockets 16 and communicating with them through box 15, are 45 two oppositely disposed tubular arms 18, at the free end of each of which is a vertical communicating socket 19. As shown, parts 14, 15, 16, 18 and 19 form an integral cored casting, the front of box 15 being closed by 50 a plate 20 and its rear having an opening covered by a cap 21. In each socket 16 is shown the end of a conduit tube 22, carrying a conducting cable 23, and extending to

the next similar fixture, not shown, or to a wall, ceiling or other fixture at the end of 55 the table. In each socket 19 is a rotatable, frictionally secured member 24, consisting of a lower tubular portion 25 and an upper cylindric clamping portion 26 having ears 27 connected by a set-screw 28. Secured for 60 frictional rotation within clamp 26 is a plug portion 29 of an arm-carrying member 30, diametrically cut away at 31 to form a port which communicates by a passage 32 with a transverse tubular portion 33, in the wall of 65 which are set-screws 34. Mounted for longitudinal and rotary movement in portion 33 is a relatively long tube 35, the inner end of which may conveniently be closed by a cap 36, while at its outer end is mounted 70 the socket 37 of an incandescent lamp 38, shown as provided with a shade 40. Near the inner end of tube 35 is cut a longitudinal aperture or slot 39.

The operation of the device will be readily 75 understood from an inspection of the drawings. It will be seen that the portion 15 forms an outlet box, within which short insulated cables 23^a are connected to cable 23, which short cables lead through arms 80 18, sockets 19, members 24 and 30, slots 39 and tubes 35 to lamps 38; and that these cables, as well as cable 23 in conduit tubes 22, are inclosed and fully protected for their 85 entire length from contact with any of the numerous metal tools, as shears, wrenches or the like, used by the operators. By the removal of cap 21 from box 15, a transverse conduit or cable may be led into or from the box. It will be seen that plug portions 90 25 and 29 rotate in planes at substantial right angles with each other and that lamp tube 35 has both longitudinal and rotary movement in portion 33, so that the lamp may be set in any desired position with relation to the work to be done. 95

In a pending application, Serial Number 749,661, filed Feb. 20, 1913, I have shown a hollow lamp support, which is capable of some of the lamp adjustments of the present 100 device. In that device, however, the conducting cable is led under the table and up through the hollow standard to each lamp or pair of lamps. In the present invention, the standard 13 supports the lamp or lamps 105 and their adjusting parts, and also the con-

duit, which extends between the series of standards, so that the entire system is completely protected.

In practice, the units sold do not include 5 the tubes 22 or 35, or the lamps or shades.

The parts are bored for standard sizes of gas-pipe or like tubing, which the assembler may cut to desired length as he sets up the system.

10 It will be understood that the number of lamps on each standard forms no part of my invention, and that other mechanical changes may be made in the device without departure therefrom.

15 What I claim is:

1. An electric lamp fixture including a standard; a box on said standard; means for supporting an end of a conduit tube in communication with said box; a tubular 20 lamp carrying arm; and hollow swiveled connections between said box and said arm constructed and fitted to permit the pivotal movement of said arm in any direction; said box, connections and arm being also constructed and fitted to inclose a conducting wire 25 passing therethrough for its entire length.

2. An electric lamp fixture including a standard; a box on said standard; means for 30 supporting an end of a conduit tube in com-

munication with said box; a slotted, tubular lamp carrying arm; and hollow swiveled connections between said box and said arm constructed and fitted to permit a limited longitudinal movement of said arm and its 35 pivotal movement in any direction; said box, connections and arm being also constructed and fitted to inclose a conducting wire passing therethrough for its entire length.

3. An electric lamp fixture including a 40 standard; a box on said standard; means for supporting an end of a conduit tube in communication with said box; and hollow swiveled connections communicating with said box and adapted to support a lamp carrying arm and to permit the pivotal movement of such arm in any direction; said box and connections being constructed and fitted to completely inclose a conducting wire 45 passing therethrough.

4. An electric lamp fixture including an integral casting comprising a standard, a box, a socket for receiving an end of a conduit tube in communication with said box and a hollow part of a swivel connection; 50 also communicating with said box.

GARRY J. DORMANDY.
